MATCH PACKET AND METHOD OF MAKING
THE SAMEJohn R. Nolan, Larchmont, N. Y., assignor to The
Diamond Match Company, New York, N. Y., a
corporation of Delaware

Application October 7, 1941, Serial No. 413,922

4 Claims. (Cl. 93—2)

This invention relates to match packets and the like and to methods of making the same, having reference particularly to packets wherein the bases of plural match combs arranged face to face are bound together and to the embracing walls of a folded cover, usually by means of wire stitching. As is well-known such packets are used extensively for advertising purposes, and in many cases they are gratuitously distributed to the ultimate purchasers of tobacco products. Consequently economy in the manufacturing cost of the packets is a desideratum.

The object of the invention is to secure the elements of the packet together without recourse to stitching, which end is attained by providing in the contiguous bases of the assembled match combs of each packet, registering apertures for the reception of a modicum of liquid adhesive when the combs are associated with the cover, which adhesive when the cover is subsequently folded closely about the bases of the combs is forced in intimate contact not only with the opposing surfaces of the combs and the cover but also with the inner surfaces of the interposed combs, all of which, together with other features of novelty, will be hereinafter more fully described, and the scope of the invention then expressed in the appended claims.

In the drawing—

Figure 1 represents a strip of connected matches having its base portion perforated in accordance with my invention.

Fig. 2 is a plan of a conventional cover for a match packet.

Fig. 3 is a perspective view of a plurality of assembled match combs with apertures therein.

Fig. 4 is a similar view showing the plural combs associated with a cover, the bases of the combs being parallel with the transverse fold line at one end of the cover.

Fig. 5 is a sectional detail, as on the line 5—5 of Fig. 4.

Fig. 6 is a view similar to Fig. 4, but showing the apertures supplied with a liquid adhesive.

Fig. 7 is a similar view showing the short fold of the cover about the bases of the match combs.

Fig. 8 is a transverse section, as on the line 8—8 of Fig. 7.

Fig. 9 is a side view of the packet, showing the perforated bases of the match combs and the folded portion of the cover in section.

Fig. 10 is a view similar to Fig. 4, but showing a modified form of aperture in the match combs.

Fig. 11 is a section, as on the line 11—11 of Fig. 10.

In carrying out my invention in the preferred way conventional match strips (Fig. 1), each comprising a series of splints extending from an uncut base or marginal portion 15, are employed. I form in the base portion small apertures 16 which are countersunk at their respective ends, as at 17, and are arranged in spaced pairs throughout the length of the base, so that when the base is severed between adjacent pairs, as indicated by the dotted lines 18, sections or "combs" 19 of suitable size for use in the production of match packets are provided, each section having therein two spaced apertures 16 adjacent the outer edge of the base.

A plurality of the counterpart perforated combs 19, usually two in number, are arranged face to face, as seen in Fig. 3, and associated with a cover 20 (Fig. 2), the bases 15 of the combs being disposed in spaced parallel relation with the lower foldable end 22 of the cover, as seen in Fig. 4. Thus the correspondingly located apertures of the plural combs are in registry and therefore in communication with each other from the external surface of the outer comb to the internal surface of the cover, as seen in Fig. 5. A modicum of liquid adhesive 21, such as glue, is entered in each of the ducts thus formed, as seen in Fig. 6, and the lower projecting end portion 22 of the cover is forcibly folded about the outer comb, as seen in Fig. 7. The walls of the cover, being pressed flat against the opposing bases of the respective combs as seen in Figs. 8 and 9 displace the liquid contents of each of the ducts and force it in intimate contact with the surfaces opposed thereto of the cover and the combs, that is to say, the adhesive exudes around the margins of the duct at the respective walls of the folded cover and also at the inner surfaces of the combs through which the duct extends.

Thus, when the adhesive sets the opposing surfaces of the combs are efficiently cemented to the respective walls of the folded cover, and the contiguous inner surfaces of the bases of the respective combs are similarly united.

Countersinking or socketing the apertures in the comb bases, as indicated at 17, contributes to the efficient exudation through a limited area of the adhesive in the region of the short overlapping end fold of the cover and also at the inner opposing faces of the associated combs; the restriction of the extent of flow of the adhesive at the fold 22 obviating the otherwise liability of cementing the marginal portion 23 of the latter, which portion is thus free to receive

and retain the free end of the cover flap 24 when the packet is closed in the usual manner.

Instead of a plurality of apertures in each comb base, a single aperture may be employed, which aperture may, if desired, be of the elongated form shown in Figs. 10 and 11. In other respects modifications may be made within the principle of my invention hereinbefore described.

I claim:

1. In a method of making a packet embodying a folded cover and a plurality of comb elements having base portions and splints extending therefrom, said base portions arranged face to face between the walls of the cover, the steps which consist in providing the bases of the respective combs with countersunk apertures which communicate with each other when the combs are associated with the cover, supplying the pre-formed apertures of the thus assembled combs with liquid adhesive, and forcibly folding a portion of the cover about the assembled comb bases, whereby the said adhesive is forced in bonding relation to the opposing surfaces of the comb bases and the cover and also to the inner surfaces of said comb bases in the region of the apertures.

2. In a method of making a packet of matches embodying a cover and a plurality of match combs attached thereto, said combs having their base portions arranged face to face, said cover having at one end a short fold overlying the bases and having at the opposite end a closure flap whereof the free end is insertable under the short fold, the steps which consist in providing the base of each of the combs with at least one countersunk aperture which is so arranged that when plural combs are assembled and associated with

the cover their respective pre-formed apertures communicate with each other, supplying the apertures of the thus assembled combs with liquid adhesive, and forcibly folding the said short fold about the assembled comb bases, whereby the said adhesive is forced in bonding relation to the opposing surfaces of the comb bases and the cover and also to the inner surfaces of said comb bases in the region of the apertures.

10 3. A packet comprising a folded cover and a plurality of comb elements having base portions and splints extending therefrom, said base portions arranged face to face between the walls at the fold of the cover and provided with countersunk apertures in communication with each other, and an adhesive extending through the said pre-formed apertures and cementing not only the opposing surfaces of the comb bases to the respective walls of the cover but also uniting the inner surfaces of said comb bases in the region of the apertures.

15 4. A packet comprising a cover and a plurality of match combs attached thereto, said combs having their base portions arranged face to face and provided with registering countersunk apertures, and said cover having at one end a short fold overlying the apertured bases and having at the opposite end a closure flap whereof the free end is insertable under the short fold, and an adhesive extending through the said registering apertures and cementing the bases to and between the walls of the folded end portion of the cover and also uniting the inner surfaces of the said comb bases in the region of the apertures.

JOHN R. NOLAN.
